APPLY

UNITED STATES PATENT OFFICE.

JOSEPH L. HERMAN, OF PEORIA, ILLINOIS, ASSIGNOR TO MIDLAND MANUFACTURING COMPANY, OF PEORIA, ILLINOIS, A CORPORATION OF ILLINOIS.

APPARATUS FOR COATING AND TREATING METALLIC MATERIALS.

Application filed February 28, 1925. Serial No. 12,341.

To all whom it may concern:

Be it known that I, JOSEPH L. HERMAN, a citizen of the United States, residing at Peoria, in the county of Peoria and State of Illinois, have invented new and useful Improvements in an Apparatus for Coating and Treating Metallic Materials, of which the following is a specification.

This invention has reference to an apparatus for coating and treating materials having an iron base and particularly the coating and treatment of wire used in the fence industry and for telephone and other purposes.

The invention has for its principal object to provide an apparatus for carrying out the process shown and described in Letters Patent issued to me October 3, 1922, No. 1,430,648, for a process of coating and treating materials having an iron base.

The invention has for a further object an apparatus of the character described, including a heat-treating furnace through which the coated material is drawn immediately upon its leaving the molten bath, and in which the coated material is heat-treated; such treatment having for its object to produce a coating more resistant to atmospheric rusting and corroding conditions than for ordinary galvanized wire, and which further will permit a heavier coated wire to be used in wire-fabricating machines without causing the coating to crack or flake off, as is the case with heavily coated galvanized wire coated by means of an ordinary galvanizing apparatus.

A still further object of the invention is to provide in a galvanizing apparatus a heat-treating furnace adapted to receive and heat-treat the coated wires immediately upon their leaving the molten-bath and in the provision of a skimming mechanism located between the molten-bath and entrance to the furnace, said skimmers adapted to remove skimmings, dross and other foreign matter which might adhere to the molten coating metal as it leaves the molten metal bath, but without materially reducing the thickness of the coating or the amount of coating metal on the wire.

A further object of the invention is to provide in a continuous wire galvanizing apparatus a skimming mechanism for removing the foreign matter which may be dragged out of the molten spelter bath by

the liquid coating, without however, removing the spelter of the coating, which includes a means of applying air or any other gaseous medium, carried at any desired temperature below the melting point of the coating material or foreign material, to chill or freeze the skimmings or foreign material upon the outside of the coated wire and forming, in effect, a molten metal tube within the skimmings or foreign material surrounding the coating on the wire. In this manner the skimmings or foreign material is skimmed off the coating without substantially or materially reducing the thickness of the coating, allowing the wire to pass on with an unwiped heavy coating of zinc spelter, which, if heated-treated, is made malleable, flexible and smooth.

That the invention may be more fully understood, reference is had to the accompanying drawings forming a part of this description, illustrating a preferred embodiment of the invention, in which:

Fig. 1 is a side elevation, on a greatly reduced scale, showing the delivery end of a zinc-spelter bath and the receiving end of a heat-treating furnace and my skimming mechanism associated therewith;

Fig. 2 is a plan view of Fig. 1;

Fig. 3 is an enlarged detail side elevation of my skimmer mechanism at the receiving end of a heat-treating furnace;

Fig. 4 is a front elevation of Fig. 3;

Fig. 5 is a cross-section through the skimmer mechanism and a partial longitudinal sectional view through the heat-treating furnace as the same would appear if taken on the line, 5—5, Fig. 4, the view further illustrating the skimming of the foreign material on the coated wire by chilling or freezing such material, but leaving a molten core for the passage therethrough of the wire with a heavy coating of zinc-spelter;

Fig. 6 is a plan view, as the same would appear if taken on the line 6—6 Fig. 5, and

Fig. 7 is a detail sectional view illustrating the means of applying an air blast.

Like characters of reference denote corresponding parts throughout the figures.

As is understood in the art of galvanizing wire, a galvanizing apparatus ordinarily includes an annealer, acid baths, a fluxing bath, a drier and a molten-metal bath, I have elected to show only the molten bath 1 and only a section of that. For the

purposes of carrying out the process of my Patent, No. 1,430,648, I also provide a heat-treating furnace 2, provided with one or more longitudinally disposed heat-treating chambers 3, through which the coated wires A are drawn and heat-treated. As the details of the heat-treating furnace form no part of the present invention, except in its association with the molten-bath and the skimming mechanism, reference will only be made thereto or such parts thereof as will illustrate the practical carrying out of the invention.

The invention, in its preferred form comprehends a round bar or rod 4 supported at the entering end of the furnace 2 and formed or provided with a plurality of spaced annular grooves 5, having preferably tapered or oppositely inclined side walls 6. Over this bar or rod 4 and through these grooves 5 travel the coated wires A, which emerge from the molten spelter bath 1 with a heavy coating of spelter and which preferably pass through the heat-treater or furnace 2, after crossing said bar or rod, for heat-treating the coated wires, in manner and for the purposes specified in my said patent. As the coated wires leave the molten spelter bath they carry with them skimmings and other foreign material, designated B, see Fig. 5, which, if not skimmed from the coated wires, will leave the coating rough and uneven and the wires unsuitable for use in fabricating machines. I provide, therefore, in connection with said bar or rod 4, and which provides one element of the skimmer, a means of cooling the bar or rod and maintain it at a desired temperature below the melting point of the coating or skimmings and foreign material, and which will chill the skimmings on contact with the bar or rod and skim the same back on the wire. The layer of spelter between the frozen exterior of the skimmings and the wire, being in a more or less molten state, a heavy but smooth coating is carried forward with the wire. This cooling means is preferably air or other gaseous medium working on the principle of an air blast and may be applied to the bar or rod at any desired points, although I prefer to apply such blasts at or near the point where the wires cross over the bar or rod. In the form shown, the cooling medium is applied externally. Such cooling means comprise, preferably, a hollow cylinder or tube 7 supported at the entrance end of the heat-treater or furnace and above the bar or rod 4, as shown, and is arranged to be connected to an air, or other gaseous source of supply, not shown. Said cylinder, or tube, is provided with a plurality of blast nozzles 8 arranged to have their openings at points approximately over the grooves 5 in the bar or rod 4, over which the wires A pass.

In my Patent, No. 1,430,648, I brought out the fact that a process, such as therein shown and described, obviated the necessity of using wipers or other smoothing mediums for the coated wires leaving the molten-bath, and which, theretofore, were considered indispensable by all wire galvanizers. The reason for this is due to the action of the heat-treating furnace, which not only heat-treats per se, but also evens up the coating as though it had been passed between wipers, and the resulting action is to produce a heavy coating, which is flexible, malleable and smooth. It is further stated in said patent that another advantage in the elimination of the wipers is that a heavier coating is permitted to remain on the wire, which, in ordinary practice, would be removed by the wipers as the wires pass therebetween. The fact that the coated wire is not wiped as it leaves the molten-bath allows a heavier coating to remain upon the wire. Such wire, when subjected to the action of the heat-treatment, will not only cause the heavy coating to distribute itself around the wire, but eliminates brittleness of the coating. Like in the process described in said patent, the present apparatus obviates the use of wipers; however, I provide a skimming mechanism located between the molten-bath and the entrance to the heating chambers of the heat-treating furnace. Such skimming mechanism neither wipes nor smooths the wires, as would wipers, such as are ordinarily used. In the art of galvanizing, several different types of wipers are employed, designated as pressure-wipers, of the screw or lever types, and charcoal wipers, such as are used in connection with the coating of telephone and telegraph wires. The skimming mechanism, which I here employ, has for its object the removal of skimmings, dross, and any foreign matter which may collect on the coatings as the coated wires emerge from the coating bath. Of course, I appreciate the fact that the surface of the molten coating metal, at the points where the wires emerge therefrom, may be kept free of dross, skimmings and foreign matter in a well known manner by the use of salammoniac, but this practice is recognized as being too costly for wire galvanizing purposes and, therefore, to insure that the coated wires shall enter the heat-treating furnace free of all dross, skimmings and foreign matter, I have provided an effective skimming mechanism, which accomplishes the purpose sought; but without in any way removing the molten-metal adhering to the wires. Furthermore, such mechanism will also prevent "reachers" forming on the wires.

What I claim is:—

1. In a continuous wire galvanizing apparatus, in combination with a tank containing

a molten-coating bath, of a heat-treating furnace, and skimming mechanism in advance of the furnace for removing foreign matter adhering to the outer surface of the 5 coating without materially reducing the thickness of the coating, including means for applying a gaseous medium for retarding the movement of the foreign material.

2. In a continuous wire galvanizing apparatus, in combination with a tank containing a molten-metal bath, of a skimming means for removing foreign matter such as dross and skimmings adhering to the outer surface of the coating, including a bar 10 providing with spaced annular grooves, through

which the coated wires are adapted to pass on leaving the metal bath and which holds back the dross and skimmings, and a series of nozzles for ejecting a gaseous medium, said nozzles being so arranged in relation to 20 the grooves in said bar as to cause the gaseous medium ejected therefrom to impinge on the coated wires passing over said bar and skim the foreign matter from the coated surface of the wires without materially reducing the thickness of the coating.

Signed at Peoria, in the county of Peoria and State of Illinois, this 23d day of Feb. 25
A. D. 1925.

JOSEPH L. HERMAN.
